EARRING

Jack H. Rude and Mary E. Rude, Steele, Mo.

Application November 7, 1952, Serial No. 22,177

Term of patent 7 years

(Cl. D45—9)

To all whom it may concern:

Be it known that we, Jack H. Rude and Mary E. Rude, citizens of the United States, residing, respectively, at Steele, in the county of Pemiscot and State of Missouri, have invented a new, original, and ornamental Design for an Earring, of which the following is a specification, reference being had to the accompanying drawing, forming a part hereof.

Figure 1 is a front elevational view of an earring, showing our new design;

Figure 2 is a side elevational view thereof; and
Figure 3 is a top plan view thereof.

We claim:

The ornamental design for an earring, as shown.

JACK H. RUDE.
MARY E. RUDE.
